UNITED STATES PATENT OFFICE

157,936

COMBINED TOOTHBRUSH AND DENTIFRICE
HOLDER

Clifton V. Berry, New York, N. Y.

Application June 3, 1947, Serial No. 139,433

Term of patent 14 years

(Cl. D4—3)

To all whom it may concern:

Be it known, that Clifton V. Berry, a citizen of the United States of America, residing at New York city, in the county of New York and State of New York, has invented a new, original, and ornamental Design for Combined Toothbrush and Dentifrice Holder, of which the following is a specification, reference being had to the accompanying drawing, forming part thereof.

In the drawings

Fig. 1 is a perspective view of a combined toothbrush and dentifrice holder showing my new design.

Fig. 2 is an end elevational view.

Fig. 3 is a front elevational view, and

Fig. 4 is a top plan view thereof.

I claim:

The ornamental design for a combined toothbrush and dentifrice holder, as shown.

CLIFTON V. BERRY.
